UNITED STATES PATENT OFFICE.

FRED M. HARRINGTON, OF WEEDSPORT, NEW YORK.

DESIGN FOR A BROILER.

SPECIFICATION forming part of Design No. 34,725, dated July 2, 1901.

Application filed March 5, 1901. Serial No. 49,973. Term of patent 7 years.

To all whom it may concern:

Be it known that I, FRED M. HARRINGTON, a citizen of the United States, residing at Weedsport, in the county of Cayuga and State of New York, have invented and produced a new and original Design for a Meat-Broiler, of which the following is a specification, reference being had to the accompanying drawings, forming a part thereof.

Figures 1 and 2 are perspective views of my design for a meat-broiler, showing the opposite upper and lower sides thereof. Figs. 3 and 4 are sectional views taken, respectively, on lines 3 3 and 4 4, Fig. 1.

As seen in the drawings, the leading or material feature of my design consists of an open rectangular frame A, having the parallel side walls *a a* and parallel end walls *a' a'*, the upper edges of the side and end walls being sur-

rounded by a marginal flange *b*, having the raised ribs *b'*, and the side walls *a a* terminating in raised ribs *c* and united by a series of separate transverse bars *d*. One of the side walls *a* consists of an open frame surrounding an elongated opening *e*.

The whole design presents a united, neat, and characteristic appearance.

Having described my invention, what I claim as new, and desire to secure by Letters Patent, is—

The design for a broiler as herein shown and described.

In witness whereof I have hereunto set my hand this 16th day of February, 1901.

FRED M. HARRINGTON.
